(54) **SPARK CATCHER**

(76) Inventor: **James W. Wapples**

James H. Waples of Wilmington, State of Delaware

Letters Patent.

The schedule referred to in this Letter Patent and making part of the same containing a description in the words of the said James H. Waples himself of his improvement in the spark catcher to be attached to the pipe of a hot engine Engine to all persons to whom these presents shall come

James H. Waples of Wilmington in the County of New Castle and State of Delaware, Engineer duly greeting —

Be it known that I the said James H. Waples, have invented constructed made and applied to use a new and useful machine called "Waples spark catcher" specified in the words following viz. The machine consists of two principle parts the catcher A, and receiver B, and is constructed of wire gauge sheet iron or tin zinc or copper the catcher is of a circular form and consists of two flanges C & D connected at the bottom forming a trough E; the inner one is connected by cross bars playing upon a spindle F closely around the exterior of the top of the smoke pipe G, the flanges to be distant from each other from four to six inches proportional however to the diameter of the pipe the flanges are to be of the same height until from the point H, opposite to the centre of the pipe when the outer one is gradually taper down in front of to the depth of an inch or thereabouts leaving an open space I between the wire gauge and the part of the flange allowing the air to pass freely in without obstruction, at that place, — The wire gauge K is attached to the outer flanges and from a point opposite the spindle to the front is to be of a coarser texture than that upon the remainder of the catcher and the receiver, The bottom edge and end to the height of the flanges are to be made of tin sheet iron, copper or other

suitable material. The bottom of the machine to be tapered off gradually until the diameter of the end is about one third of the greatest diameter of the catcher. The height of the end to be about two thirds of the greatest height of the catcher which is to be about equal to the lateral distance west opposite the center of the smoke pipe. The receiver or catcher is the catcher by a hinge L at the top. — The operation of the machine is as follows: The machine itself being like a scoop will always present its front to the wind-sparks rising from the smoke pipe and the wire gauge being distant from the upper surface they fall into the space between the flange and the air flowing briskly through the small opening in front run through the wire gauge transfer to carry them down into the receiver which retains them until they condense themselves. The whole machine is covered with wire gauge. The cleaning the receiver is effected by a bent lever M attached to a hinge N to the bottom of the catcher immediately under the hinge of the receiver the lever being so made that when the end is drawn round by a wire or wire O it throws up the receiver and the sparks, ashes &c. then fall out.

What I claim as my invention and which I desire to secure by a letter patent is the before described spark catcher and receiver and the mode of cleaning the receiver.
